The ornamental design for a lick plate for pets, as shown and described.

DESCRIPTION

FIG. 1 is a top perspective view of a lick plate for pets, showing my new design;

FIG. 2 is a bottom perspective view thereof;

FIG. 3 is a top perspective view of the lick plate for pets in another angle;

FIG. 4 is a front elevational view thereof, the rear elevational view being a mirror image of FIG. 4;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2; and,

FIG. 12 is a partial enlarged view of FIG. 3.

The broken lines in the figures are for the purposes of illustrating portions of the lick plate for pets, which form no part of the claimed design.

The dash-dot-dash broken lines are for notating enlarged views, and form no part of the claim design.
